UNITED STATES PATENT OFFICE.

CYRILLE CÔTE, OF PARIS, FRANCE, ASSIGNOR TO SOCIÉTÉ DES ÉTABLISSEMENTS CÔTE, OF PANTIN, FRANCE.

TWO-CYCLE EXPLOSION-MOTOR.

1,072,314.

Specification of Letters Patent.

Patented Sept. 2, 1913.

Application filed December 2, 1908. Serial No. 465,597.

To all whom it may concern:

Be it known that I, CYRILLE CÔTE, citizen of the United States, residing at 24 Rue de Navarin, Paris, in the Republic of France, have invented new and useful Improvements in Two-Cycle Explosion-Motors, of which the following is the specification.

The present invention relates to improvements in two cycle combustion engines, the primary object thereof being to so construct the cylinder elements that the assembling or disassembling of the engine will be greatly facilitated.

A further object of the above invention is to construct the cylinder elements in sections and to insert a segment element between two of the adjacent sections to prevent the escape of the gas from the cylinders.

Other objects and advantages will appear from the following description with reference to the accompanying drawings, wherein:

Figure 1 is a transverse vertical sectional view of an engine embodying my invention. Fig. 2 is a longitudinal vertical section of the same.

Referring more specifically to the drawing wherein like reference characters indicating like parts throughout the different views, the letters A and C designate the piston and pump cylinders respectively, which are arranged in superposed position on the crank case D, wherein the driving shaft E is mounted together with the cranks e and e¹.

The piston cylinder A, has two side walls a¹ and a² the inner wall thereof being offset at its base as at a³, while the pump cylinder, upon which the cylinder A rests, has an annular flange e¹ to form a seat therefor, the diameter of the flanged portion thereof being substantially the same as the diameter of the central portion of the piston cylinder. Formed integral with the piston cylinder A are the caps H which are provided with apertures to receive the bolts on stays G, these bolts or stays being screw threaded at their lower extremities as at g, whereby they are screwed into the threaded bores formed in the crank case D. It will be seen that in the assembling of the parts, the pump cylinder C is placed on the crank case D while the piston cylinder, the central diameter of which is smaller than the corre-

sponding diameter of the pump cylinder, is seated on the flanged end of the pump cylinder. Because the inner wall of the piston cylinder is offset at its base, an annular depression M is formed. This depression M, is adapted to receive the steel segment I, which is, of course, placed in position when assembling the different parts. This steel segment I, insures the absolute tightness of the pump and suppresses any escape of gas on account of its being made smaller in diameter than the piston, so as to fit tightly around it.

When the above named parts are placed in their proper position, together with the piston K, which has its lower portion of a greater diameter than the upper part thereof, the bars or bolts G are passed through the caps H and are screwed into the bores in the crank case D, thus bringing all of the sections as tightly together as possible. The piston K is provided with a plurality of annular grooves, wherein a plurality of packing members or washers L are secured.

What I claim and for which I desire to secure Letters Patent is:—

1. In a combustion engine, the combination with an engine cylinder having an annular aperture at its base, of a pump cylinder of larger diameter than, and in alignment with said engine cylinder, a centering flange at the upper end of the pump cylinder in engagement with said aperture, a common piston for both cylinders built on two diameters, a crank shaft case below the pump cylinder; said annular aperture, centering flange and the wall of the piston forming a packing chamber; a packing comprising annular metal sections, in said chamber, said metal sections fitting tightly around the piston, so as to prevent leakage around it; bolts for clamping together said engine and pump cylinders and said crank shaft case, whereby on tightening said bolts, said metal sections will be compressed in said chamber by said centering flange to form a tight joint between said engine and pump cylinders.

2. In a combustion engine, the combination with a plurality of engine cylinders each having an annular aperture at its base, of a plurality of pump cylinders of larger diameter than, and in alignment respectively with said engine cylinders, a centering flange at the upper end of each pump cyl-

inder in engagement with said aperture, a common piston for each pair of cylinders built on two diameters, a crank shaft case below each pump cylinder; said annular 5 aperture, centering flange and the wall of the piston forming a packing chamber; a packing comprising annular metal sections in said chamber, said metal sections fitting tightly around the piston, so as to prevent 10 leakage around it; bolts for clamping together said engine and pump cylinders and said crank shaft case, whereby on tightening

said bolts said metal sections will be compressed in said chamber by said centering flange to form a tight joint between said 15 engine and pump cylinders.

In testimony whereof I have hereunto set my hand in the presence of two subscribing witnesses.

CYRILLE CÔTE.
